(57) **CLAIM**

The ornamental design for a bucket lid LED light, as shown and as described.

DESCRIPTION

FIG. 1 is a right front top perspective view of a bucket lid LED light according to this disclosure;

FIG. 2 is a right elevation view of an exploded view of the bucket lid LED light of FIG. 1;

FIG. 3 is a right front top perspective view of an exploded view of the bucket lid LED light of FIG. 1;

FIG. 4 is a left front top perspective view of an exploded view of the bucket lid LED light of FIG. 1;

FIG. 5 is a right bottom perspective view of an exploded view of the bucket lid LED light of FIG. 1;

FIG. 6 is a front bottom perspective view of an exploded view of the bucket lid LED light of FIG. 1;

FIG. 7 is a left bottom perspective view of an exploded view of the bucket lid LED light of FIG. 1;

FIG. 8 is a back bottom perspective view of an exploded view of the bucket lid LED light of FIG. 1;

FIG. 9 is a top elevation view of the bucket lid LED light of FIG. 1;

FIG. 10 is a bottom elevation view of the bucket lid LED light of FIG. 1;

FIG. 11 is a right elevation view of the bucket lid LED light of FIG. 1;

FIG. 12 is a left elevation view of the bucket lid LED light of FIG. 1; and,

FIG. 13 is a front elevation view of the bucket lid LED light of FIG. 1.

The broken lines are shown for environmental purposes only and form no part of the claimed design.

1 Claim, 13 Drawing Sheets
